UNITED STATES PATENT OFFICE.

JOHN ELLIOTT JENKINS, OF CHICAGO, ILLINOIS.

DESIGN FOR AN ATTACHMENT FOR AUTOMOBILE-RADIATORS.

49,732.

Specification for Design.

Patented Oct. 3, 1916.

Application filed July 12, 1915. Serial No. 39,493. Term of patent 3½ years.

To all whom it may concern:

Be it known that I, JOHN ELLIOTT JENKINS, a citizen of the United States, residing at Chicago, in the county of Cook and State of Illinois, have invented a new, original, and ornamental Design for an Attachment for Automobile-Radiators, of which the following is a specification, reference being had to the accompanying drawing, forming part thereof.

The figure is an elevation of my design as applied to an attachment for automobile radiator.

I claim:

The ornamental design for an attachment for automobile radiator, as shown.

JOHN ELLIOTT JENKINS.
